(57) **CLAIM**

The ornamental design for cup holder for couches and sofas, as shown and described.

DESCRIPTION

FIG. 1 is a perspective view of a first cup holder showing our new design;

FIG. 2 is a side view of the first cup holder shown in FIG. 1;

FIG. 3 is another side view of the first cup holder shown in FIG. 1;

FIG. 4 is a top plan view of the first cup holder shown in FIG. 1; and,

FIG. 5 is a bottom plan view of the first cup holder shown in FIG. 1.

Any surface shading is used solely to show the character or contour of the surface represented.

1 Claim, 5 Drawing Sheets
